UNITED STATES PATENT OFFICE.

FRANK A. NEWELL, OF TERRY, MONTANA.

AEROPLANE AIR-SHIP.

No. 928,687.

Specification of Letters Patent. Patented July 20, 1908.

Application filed December 4, 1908. Serial No. 465,930.

To all whom it may concern:

Be it known that I, FRANK ALBERT NEWELL, a citizen of the United States of America, and a resident of Terry, in the county of Custer, in the State of Montana, have invented certain new and useful Improvements in Aeroplane Air-Ships, of which the following is a specification.

The object of this invention is to provide an aeroplane air ship having means automatically operative for maintaining its equilibrium and conveniently adjustable, in case of accident to the machinery, into position to retard and prevent sudden and dangerous descents of the ship.

The invention consists in certain improvements as hereinafter claimed in the shape of the wings constituting the aeroplane, in the duplex arrangement of such wings, in a double set of such duplex wings and in means for swiveling one set thereof with reference to the other set into position for retarding a sudden downward flight of the ship.

The invention comprises other features hereinafter claimed.

Figure 1 of the accompanying drawings represents a side elevation partly in section on line 1—1 of Fig. 2 of an aeroplane air ship embodying one form of this invention. Fig. 2 represents a vertical transverse section thereof on line 2—2 of Fig. 1. Fig. 3 represents a top plan view thereof. Fig. 4 represents a longitudinal section on line 4—4 of Fig. 2 through one of the aeroplane wings near the inner end thereof. Fig. 5 represents a longitudinal section on line 5—5 of Fig. 2 of such wings near the outer end thereof. Fig. 6 represents a horizontal section on an enlarged scale on line 6—6 of Fig. 1. Fig. 7 represents on an enlarged scale in side elevation and partly in section the mechanism for turning or swiveling the upper duplex aeroplane. Fig. 8 represents a bottom plan view of said mechanism showing the means for locking the lever and controlling the positions of said upper aeroplane. Figs. 9, 10 and 11 represent transverse sections of different forms of hollow ribs for the wings.

The same reference numbers represent corresponding parts in the different figures.

A central vertical tubular standard 10 serves as the main support to which the different parts of the machine are secured. This standard 10 has at its upper end a

flange or collar 11 and at its lower end a flange or collar 12. The flange 12 is provided with slots 13 and 14 disposed at right angles to each other and serving as locking catches as hereinafter described.

A duplex aeroplane is secured to the standard 10 and comprises two similar wings 20 and 30 disposed substantially parallel with and apart from each other on opposite sides 65 of said standard. Each of these wings is of ogee form in cross section having a downward curvature along its inner portion and an upward curvature along its outer portion. The downward curve forms a large 70 hook shaped concavity 21 on the under side of the wing which concavity extends throughout the length thereof and is open at both ends. The upward curve along the outer portion of the wing forms a convexity 75 22 which also extends throughout the length of the wing. The curvature at the inner side of the wing includes a return curve which closes that side and prevents the passage or escape of air from one side of the 80 duplex aeroplane to the other side thereof. Brace rods 23, disposed at intervals along the length of the wing, connect the hook-shaped inner part thereof with the convex outer part thereof, these brace rods being approximately two-thirds of the width of the wings. The wing is provided with marginal and intermediate transverse stiffening ribs 24. These ribs are preferably constructed of nickel steel, aluminum or other suitable material, and they are preferably made hollow or tubular as shown in Figs. 9, 10 and 11 for lightness, and are preferably charged with a compressed gaseous fluid to impart stiffness thereto. The inner bulging 95 edges 25 of the wings 20 and 30 are preferably rounded longitudinally toward the center as shown in Fig. 3. A connecting brace 26 is united at its opposite ends to the adjacent inner sides of the wings 20 and 30, and the standard 10 passes through the center of this brace. Brace rods 27 connect the upper end of the standard 10 with the wings 20 and 30, on opposite sides thereof.

A vertical shaft 40 is journaled in the hollow standard 10 and extends above the top thereof. This shaft is provided about midway of its length with a fixed collar 41 which rests on the fixed collar 11 of said standard, said collar 11 serving as a bearing on which the shaft 40 swivels. The lower end of the shaft 40 is provided with a

lug 42 which projects below the bottom of the tubular standard 10 and a hand lever 45 is pivoted to said lug and adapted to serve as a means for turning the shaft 40 in the standard 10. A spring 46, attached to the lower end of said lug, serves at its free end as a rest for said lever and holds the latter in horizontal position in engagement with the notch 13 or the notch 14 into either of which 10 the lever may be adjusted by the operator.

An upper duplex aeroplane is secured to the shaft 40 above the standard 10. This aeroplane comprises also two similar wings 50 and 60, also constructed in ogee form 15 transversely, and of a size and character similar to the wings 20 and 30 of the lower aeroplane. These wings 50 and 60 are disposed in closer proximity to each other than the wings 20 and 30. Plates 51 and 20 61, disposed at different heights on the shaft 40, connect the inner bulging ends of wings 50 and 60 with each other and with said shaft, and brace rods 52 and 62 connect the inner lower edges of said wings with the 25 collar 41 of the shaft 40 as shown in Fig. 2.

A car 70 is secured at its top to the lower inner edges of the wings 20 and 30 of the lower duplex aeroplane and the standard 10 projects downward through the top of 30 said car as shown in Fig. 2. The car is shown as inclosed but the sheathing thereof may be omitted, and the car is preferably in the form of an open skeleton frame. The car is provided underneath with front trucks 35 71 and rear trucks 72, supported in suitable dependent frames, the front trucks being preferably larger than the rear trucks. The car is also provided at its front end with a forwardly extended rudder frame 73 and at 40 the rear end with a rearwardly extended rudder frame 74 and also with a further extended rudder frame 75.

A motor 80, preferably an internal combustion engine is disposed in the forward 45 part of the car 70 and a seat 85 is disposed in the rear part thereof.

A propeller shaft 90 is disposed longitudinally on the machine and journaled in standards 91 and 92 secured to the top of 50 the car 70. This shaft is provided at its front end with a propeller 93 and at its rear end with the pulley 94, the latter being connected with the driving pulley 81 of the motor by means of a belt 82. The propeller 55 is preferably of the form shown in my Patent No. 799,800, dated Sept. 19, 1905.

A horizontally pivoted rudder 100 is supported in the front frame 73 and a horizontally pivoted rudder 105 is supported in the 60 rear frame 75, these rudders being adapted for use in guiding the machine upward and downward. The front rudder 100 is provided on its upper side with a lateral arm 101 and on its underside with a lateral arm 65 102 for connection with the pulley cords and

with a slot 103 to avoid such cords in its upward and downward swing. The rear rudder 105 is also provided with lateral arms 106 and 107 extending upward and downward for connection of the pulley cords. 70

A vertically pivoted rudder 110 is supported in the rear frame 75 and serves to guide the machine laterally. This rudder is provided with lateral arms 111 and 112 for connection of the pulley cords or rods. 75

A horizontal foot lever 115 is pivoted in front of the operator's seat 85 and opposite ends thereof are connected by cords 116 and 117 passing through pulleys 76-77 and 78-79 with the lateral arms 101 and 102 of the front rudder 100. This foot lever is also connected at its opposite ends by rods or cords 118 and 119 with the lateral arms 106 and 107 of the horizontal rudder 105. 80

A horizontally pivoted foot lever 120 is supported slightly in the rear of the foot lever 115 and connected at its opposite ends by rods or cords 121 and 122 with the lateral arms 111 and 112 of the rear vertical rudder 110. Under this arrangement of the 85 foot levers, both are easily accessible to the operator. The horizontal rudders are so connected with their foot levers that when the front rudder 100 is inclined downward and rearward from its pivotal point as shown in 90 full lines in Fig. 1, for upward flight, the rear horizontal rudder 105 is inclined upward and rearward from its pivotal point as shown in full lines in said figure, to aid its upward flight. When the front rudder 100 is inclined upward and rearward as shown in the upper dotted outline in Fig. 1 to induce downward flight of the machine, the rear horizontal rudder 105 is inclined downward as shown in the lower dotted outline 95 100 in said figure to aid in such downward movement.

Each of the wings of either of the duplex aeroplanes is approximately square in plan view, its inner edge being convex as shown 105 in Fig. 3 and its outer corners being preferably rounded as there shown. These wings may be of any suitable size or proportions. In one form I use them of say sixteen feet in length and of a corresponding 110 breadth so that the duplex aeroplane comprising the two wings side by side will cover thirty-two feet, more or less, in the upper duplex aeroplane and a larger span in the lower duplex aeroplane, such wings being 115 120 farther apart than in the upper aeroplane.

In the use of this machine, the operator will adjust the horizontal rudders substantially in the positions shown in Fig. 1 for the start in the upward flight. The motor is then started and the propeller will draw the machine in the direction of the arrow of Fig. 1, causing it to travel on its trucks in its initial movement. As its speed increases 125 the horizontal rudders guide it off the 130

ground and it takes its flight in air. The inner curves of the two wings of each aeroplane together with the outer upward curves thereof tend to maintain the machine in upright position. If the machine tips the pressure of the air against the inner concavity of the wings of the downward-tilting side tends to lift said side and the upward curves of the wings at the opposite side of the machine permit the free escape of the air from the concave chambers of the wings of that side, whereby the pressure on that side is relieved, and the machine rights itself, returning to its normal position.

15 In case an accident happens to the machinery causing the propeller to stop and the machine to commence a sudden descent, the operator swings the lever 45 a quarter turn, whereby the upper swiveling duplex aeroplane is shifted into position at right angles to the lower duplex aeroplane. Then the outer ends of the wings of the upper aeroplane project beyond the sides of the wings of the lower aeroplane and act somewhat 25 after the manner of a paraehute to arrest a sudden and dangerous descent of the machine. The machine will then descend slowly with more or less swaying from side to side.

30 I claim as my invention:

1. A wing for an air ship formed along its inner portion with a longitudinally extended downward curvature and along its outer portion with a longitudinally extended 35 upward curvature, the downward curvature embracing a return curve.

2. A wing for an air ship having along its inner portion a downward hook-shaped curvature extended throughout its length 40 and along its outer portion an upward convex curvature.

3. A wing for an air ship shaped transversely in ogee form and having its downward concave curvature along its inner portion 45 and its upward convex curvature along its outer portion, the concave curvature embracing a return curve which closes the inner side of the wing.

4. A wing for an air ship shaped transversely in ogee form and having its larger concave curvature along its inner portion and its smaller convex curvature along its outer portion, the inner edge of said wing being slightly bowed.

5. An aeroplane for an air ship comprising two wings disposed side by side, each wing being formed along its inner portion with a longitudinally extended downward curvature forming a concave chamber open 55 at both ends and along its outer portion with a longitudinally extended upward curvature, said downward curvature embracing a return curve which closes the inner side of the wing.

6. An aeroplane for an air ship comprising two wings disposed apart from each other side by side, each wing being formed along its inner portion with a longitudinally extended downward curvature forming a concave chamber open at both ends and along its outer portion with a longitudinally extended upward curvature, said downward curvature embracing a return curve which closes the inner side of the wing. 65

7. The combination of two duplex aeroplanes disposed one above another and each 75 comprising ogee wings disposed side by side, and means for turning one of said aeroplanes relatively to the other.

8. The combination of two duplex aeroplanes disposed one above another and each 80 comprising ogee wings disposed side by side, and means for turning and locking one of said aeroplanes at right angles to the other.

9. A duplex aeroplane comprising two ogee wings disposed side by side, said wings having large downward concave curvatures along their inner portions and smaller upward convex curvatures at the outer portions, said downward concave curvature embracing a return curve which closes the inner 85 side of the wing.

10. A duplex aeroplane comprising two ogee wings disposed parallel with and apart from each other and having large downward concave curvatures along their inner portions and upward convex curvatures along their outer portions, said downward curvatures embracing return curves which close the inner sides of the wings, and a propeller disposed between the closed inner side of 100 said wings.

11. An aeroplane air ship comprising a tubular standard, a duplex aeroplane secured to said standard, a vertical shaft swiveled in said standard and projecting above the top 105 thereof, a duplex aeroplane secured to said shaft, and means for turning said shaft to change the relative positions of said aeroplanes.

12. A combination in an aeroplane air ship 110 of a tubular standard provided with catches at its lower end disposed at different angles to each other, an aeroplane secured to said standard, a vertical shaft swiveled in said standard and extending beyond the top 115 thereof and provided with a lug projecting below the bottom thereof, an aeroplane secured to said shaft; a lever pivoted to said lug and adapted to engage said catches and a spring for holding said lever in locked position. 120
